(57) **CLAIM**

I claim the ornamental design for a pottery wheel, as shown and described.

DESCRIPTION

FIG. 1 is a left perspective view of a pottery wheel.

FIG. 2 is a front elevation view of the pottery wheel illustrated in FIG. 1.

FIG. 3 is a rear elevation view of the pottery wheel illustrated in FIG. 1.

FIG. 4 is an elevation view of left side of the pottery wheel illustrated in FIG. 1.

FIG. 5 is an elevation view of the right side of the pottery wheel illustrated in FIG. 1.

FIG. 6 is a top view of the pottery wheel illustrated in FIG. 1; and,

FIG. 7 is a bottom view of the pottery wheel illustrated in FIG. 1.

The broken line cord is shown broken away to indicate no particular length.
